UNITED STATES PATENT OFFICE.

EMIL LARSON, OF CHICAGO, ILLINOIS.

RULING-MACHINE GUIDE.

Application filed April 3, 1922. Serial No. 548,946.

To all whom it may concern:

Be it known that I, EMIL LARSON, a citizen of the United States, residing at Chicago, in the county of Cook and State of Illinois, have invented certain new and useful Improvements in Ruling-Machine Guides, of which the following is a specification.

This invention relates to means for adjusting the bar which guides the sheets on a feed table to a ruling machine and its object is to provide adjusting means which can be operated by the ruler without leaving his position adjacent the ruling pens and which, therefore, enables quicker and more accurate 15 adjustments and tends to produce better and a greater amount of work with less labor on the part of the ruler.

Further objects of the invention are to provide means conveniently located for 20 easily and quickly adjusting the sheet guide angularly on the feed table; to enable the adjustment of the sheet guide bodily to any desired position on the feed table; to lock the sheet guide rigidly in any adjusted position; and to locate the adjusting and locking means adjacent the upper end of the stock support so that the ruler may reach the same without leaving his position at the 25 ruling pens.

30 In the accompanying drawing, I have illustrated a selected embodiment of the invention and referring thereto—

Fig. 1 is a plan view illustrating the invention embodied with those parts of a ruling machine with which it is immediately associated;

Fig. 2 is a plan view of the pivoted base member of the adjusting means;

Fig. 3 is a transverse sectional view on the line 3—3 of Fig. 1; and

Fig. 4 is a transverse sectional view on the line 4—4 of Fig. 1.

Referring to the drawings, 5 is a stock supporting table, 6 a feed table and 7 indicates generally the operative mechanism of a ruling machine. My invention is adaptable to ruling machines of different varieties and for this reason and because it relates only to the sheet guide, I do not deem it necessary to show or describe more of the ruling machine since those skilled in the art will readily understand the invention as it is illustrated and described herein.

The sheet guide 8 is carried by two parallel slide bars 9, 9 and is adapted to be adjusted bodily and angularly on the feed

table by corresponding movement of said parallel slide bars.

A base plate 10 is pivotally mounted at 11 on the top or on the underside of the stock table. I have shown the invention exposed on the top of the stock table but this is for illustration and I propose to provide a suitable covering for the invention when so used, or to place it on the underside of the stock table. This base plate rests upon the stock support adjacent the upper edge thereof and it is provided on its upper face with a fixed longitudinal guide bar 13 and with a clamping bar 14 which is pivoted at 15 to the base plate 10 and to the plate 16 carried by the fixed guide bar 13. The slide bars 9 which carry the sheet guide 8 are arranged to slide on the fixed guide bar 13 engaging opposite edges thereof and a plate 17 fastened to the two slide bars projects over the guide bar 13 and the clamping bar 14. Thus the two plates 16 and 17 fastened, respectively, to the guide bar and to the slide bars constitute guides for the bars to hold 20 them in their proper relation at all times and yet permitting the adjustment of the slide bars relative to the guide bar and of the clamping bar relative to the other bars as desired.

25 A transverse bracket 18 is fastened to the base plate at the outer end thereof and it has a down-turned end located adjacent the edge of the stock support. Another bracket 20 is fastened to the underside of the stock support beneath the bracket 18 and it has an upturned end 21 located in front of and spaced from the down-turned end 19 and registering therewith. A screw bolt 22 is secured rigidly in the down-turned end 19 by the nut 23 and it projects through the upturned end 21 and carries the knurled adjusting nuts 24 and 25 on opposite sides of said upturned end. By adjusting these nuts 24 and 25 the base and the bars carried thereon can be swung on the pivot 11 to adjust the sheet guide 8 angularly on the feed table to a very fine degree in either direction. Then the nuts can be tightened to lock the base in its adjusted position.

30 The ends 13' and 14' of the bars 13 and 14 adjacent the sheet guide are formed into eyes to receive the bolt 26 which has its headed end seated in the eye 13' of the fixed guide bar 13 and its threaded end projecting through the unthreaded eye 14' of the clamping bar 14 and carrying a knurled adjust-

ing nut 27 on its outer end to bear against the eye 14'. This clamping bar has a cam 28 on its edge to engage the adjacent edge of the slide bar 9 and when the slide bars 5 have been moved longitudinally to adjust the sheet guide bodily on the feed table the nut 27 is tightened to swing the clamping bar into clamping position against the edge of the adjacent slide bar and to clamp said 10 slide bar between the clamping bar and the fixed guide bar. The clamping bar with its cam provides a strong and efficient locking device which can be easily applied or released by manipulating the knurled nut 27.

15 My invention provides a simple but effective means whereby the sheet guide for a ruling machine may be readily and easily adjusted by the ruler without leaving his position adjacent the pens where he usually 20 stands. The angularity of the sheet guide may be adjusted without releasing the clamp 14 by swinging the base on its pivot 11, this being accomplished by manipulating the knurled nuts 24 and 25. Thus the angularity of the sheet guide may be adjusted to 25 a very fine degree relative to the feed table and without changing the position of the sheet guide relative to the pens of the ruling machine and because this adjustment can 30 be easily and quickly made the ruler is enabled to keep his work more uniform and with less labor than has heretofore been possible with guide adjustments which require the ruler to leave his post at the pens 35 and walk around to the front of the feed table. And the sheet guide may be adjusted bodily across the feed table after releasing the clamp by sliding the slide bars 9 relative to the fixed guide bar 13 to any adjusted 40 position, and a few turns of the knurled nut 27 will retain the clamping bar in locked position on its adjacent slide bar to hold the sheet guide rigidly in its adjusted position.

45 I have illustrated the invention in a simple form which I have found in practical use to be entirely satisfactory for the intended purpose but I am aware that various changes in the form, construction and arrangement of parts may be made without departing from the spirit or sacrificing the 50 advantages of the invention and I reserve the right to make all such changes as fairly fall within the scope of the following claims.

I claim:

55 1. In a ruling machine, the combination of a stock table, a sheet guide, means on the stock table for supporting said guide, and means on the stock table for adjusting the support to adjust the guide angularly, about 60 a pivotal center fixed with respect to the stock table.

65 2. In a ruling machine, the combination of a stock table, a sheet guide, movable means on the stock table for supporting said guide to adjust the guide bodily, and

means on the stock table for guiding said support about a pivotal center fixed with respect to the stock table.

3. In a ruling machine, the combination 70 of a stock table, a sheet guide, movable means for supporting said guide, and means at the inner edge of the stock table for locking the supporting means in adjusted position, said supporting means being pivotally connected to the stock table.

4. In a ruling machine, the combination 75 of a stock table, a sheet guide, means located adjacent the inner edge of the stock table for supporting said guide and movable to adjust the guide bodily, means for adjusting the support to adjust the guide angularly, about a pivotal center fixed with respect to the stock table, and means for locking the support in adjusted position.

5. In a ruling machine, the combination 80 of a stock table, a sheet guide, a base pivoted on the stock table, a support for the guide and movably mounted on the base, and means for locking the support in adjusted position on the base.

85 6. In a ruling machine, the combination of a stock table, a sheet guide, a base pivoted on the stock table, a support for the guide arranged on the base, and means for swinging the base to adjust the guide angularly.

90 7. In a ruling machine, the combination 95 of a stock table, a sheet guide, a base pivoted on the stock table, a support for the guide arranged on the base, means for locking the support in place on the base, and means for swinging the base to adjust the guide angularly.

100 8. In a ruling machine, the combination 105 of a stock table, a sheet guide, a base pivoted on the stock table, a support for the guide arranged on the base and movable relative to the base to adjust the guide bodily, means for swinging the base to adjust the guide angularly, and means for locking the support in adjusted position.

110 9. In a ruling machine, the combination 115 of a stock table, a sheet guide, a base pivoted on the stock table, and a support for the guide mounted on the base and movable independently of and conjointly with the base to adjust the sheet guide.

120 10. In a ruling machine, the combination of a stock table, a sheet guide, a base pivoted on the stock table, a guide bar on the base, a pair of supporting bars connected to the sheet guide and slidably arranged on the base on opposite sides of the guide bar, and means for locking the guide in adjusted position.

125 11. In a ruling machine, the combination 130 of a stock table, a sheet guide, a base pivoted on the stock table, a guide bar on the base, a pair of supporting bars connected to the sheet guide and slidably arranged on the base on opposite sides of the guide bar, and

means for swinging the base to adjust the sheet guide angularly.

12. In a ruling machine, the combination of a stock table, a sheet guide, a base pivoted on the stock table, a guide bar on the base, a pair of supporting bars connected to the sheet guide and slidably arranged on the base on opposite sides of the guide bar, means for swinging the base to adjust the sheet guide angularly, and means for locking the base in adjusted position.

13. In a ruling machine, the combination of a stock table, a sheet guide, a base pivoted on the stock table, a guide bar on the base, a pair of supporting bars connected to the sheet guide and slidably arranged on the base on opposite sides of the guide bar, means for swinging the base to adjust the sheet guide angularly, means for locking the base in adjusted position, and means for

locking the supporting bars in adjusted position.

14. In a ruling machine, the combination of a stock table, a sheet guide, a base pivoted on the stock table, a support for the sheet guide slidably mounted on the base to adjust the guide bodily, a clamping lever pivotally mounted on the base and arranged to engage the support, and means for operating on said lever to lock the support in adjusted position.

15. In a ruling machine, the combination of a stock table, a sheet guide, a base pivoted on the stock table, a support for the base, a support for the sheet guide mounted on the base and movable conjointly therewith, and an adjusting screw device for swinging the base and locking it in adjusted position.

EMIL LARSON.
